CLAIM

The ornamental design for a floor scrubbing machine, as shown and described.

DESCRIPTION

FIG. 1 is a top, front and left side perspective view of a floor scrubbing machine showing our new design;

FIG. 2 is a top plan view thereof;

FIG. 3 is a front elevational view thereof;

FIG. 4 is a rear elevational view thereof; and,

FIG. 5 is a right side elevational view thereof, the left side being a mirror image.

The undisclosed bottom view is plain and unornamented.

FIG. 1

FIG. 2

FIG. 3

FIG. 4

FIG. 5
